UNITED STATES PATENT OFFICE.

ALBERT V. WILSON AND HAROLD F. WILSON, OF LOS ANGELES, CALIFORNIA.

DOG-RACING APPARATUS.

Application filed March 28, 1927. Serial No. 178,896.

This invention relates to a mechanical dog racing apparatus. Such an apparatus usually embodies a track along which a carriage or car is driven by means of a motor. This carriage supports a lure for the dogs which may be in the form of a rabbit. The rabbit is propelled at a high speed and cannot be overtaken by the dogs. The pack of dogs race along the track after the rabbit and this affords amusement to the spectators as well as an opportunity to bet on the result of the race of the dogs.

As usually constructed, the track is a cumbersome construction involving the use of two rails along which a car is driven. This car is provided with a projecting arm which carries the rabbit in plain view of the dogs and near the ground. The construction is a permanent one and it can not be used in connection with ordinary race tracks for horses because its removal entails too much expense. The general object of this invention is to provide an apparatus of this kind in which a track of simple construction is provided which will enable the rabbit or lure for the dogs to be carried and propelled along at a high speed, and at the same time to construct the apparatus in such a way as to facilitate its removal from the race course. Hence, the apparatus can be used on an ordinary race course and removed when it is not wanted, leaving no obstructions on the course.

A further object of the invention is to provide simple means for operating the mechanical rabbit so as move it up and down from time to time as it speeds along the track, thereby simulating jumping of a live rabbit.

Further objects of the invention will appear hereinafter.

The invention consists of the novel parts and combinations of parts to be described hereinafter, all of which contribute to produce an efficient dog racing apparatus.

A preferred embodiment of the invention is described in the following specification, while the broad scope of the invention is pointed out in the appended claims.

In the drawings:

Figure 1 is a plan of a race course for dogs embodying the invention, the same being broken away at its middle portion. In this view the carriage and apparatus associated with it are shown upon a greatly enlarged scale with respect to the race track.

Figure 2 is a vertical cross section taken about on the line 2-2, Figure 1, upon an enlarged scale and illustrating details of the apparatus.

Figure 3 is a plan of the apparatus showing a short portion of the track broken away.

Figure 4 is a side elevation of the apparatus showing a portion of the track as viewed from the inner side, that is to say, the side opposite to the location of the "rabbit"; this view diagrammatically illustrates the wiring to the power rail which supplies electric current to the motor.

Figure 5 is a view similar to Figure 4 but showing the opposite side of the carriage and the opposite side of the fence.

In practicing the invention, we provide a track 1 which is in the form of a fence provided with a plurality of posts such as the post 2, and constructed so that the entire fence can be readily taken apart and removed. For this purpose, each post is provided with a power rail 3 which is mortised into a notch or recess 4 on the side of each post so that the outer side of the rail 3 is flush with the side of the post. A similar rail 5 is mounted in a similar manner on the same side of the post, but this rail operates as a traction rail, being provided with an "angle" or channel 6 which may be attached to its outer face and along which runs a wheel 7 which drives a carriage 8 along the track. This carriage may be of any suitable construction. As illustrated, it is of a skeleton form built up of metal bars, the upper portion of the carriage being provided with two wheels 9 which run along on a top rail 10 which extends along the upper side of the fence and completes the track. The carriage 8 supports a motor 11 which is preferably an electric motor.

The motor 11 is preferably supported on the side of the track opposite to the lure or "rabbit" 12, and for this purpose, the carriage includes a bracket 13 which extends down on the inner side of the fence or track. This bracket supports the driving wheel 7 in position to enable it to run on the face of the angle iron or channel 6 with the wheel disposed below the flange 14 of the angle iron.

On the side of the track opposite to the rails 3 and 4, we provide a guide rail 15 which is mortised into a notch in the face of the post so that the face of this rail is flush with the face of the post. This rail is

preferably disposed near the ground and operates as a guide for a roller 16 carried on the lower end of a bracket 17 which forms the part of the carriage which is disposed 5 on the outer side of the fence. This roller 16 is preferably guided along an iron guide bar 18 which may be of angle iron or channel form, and which forms a part of the guide rail 15. If desired the posts 2 may be 10 planted directly in the earth and removed when the apparatus is not wanted, but if desired, the lower ends of the posts may be stepped in small concrete piers 19 having sockets 20 on their upper sides to fit the 15 square form of the posts.

The motor 11 is preferably an electric motor and is connected by any suitable means, such as bevel gears 21, with the wheel 7 to drive the wheel. Any suitable electric 20 current may be used for driving the motor. As illustrated in Figure 4, this current is supposed to be a 3-phase current involving the use of two conductor bars 22 extending along the power rail 3 and insulated from 25 it. In addition to this, a return conductor bar 23 is provided which extends along the power rail 3. These three contact rails are in contact with insulated brushes 24 which are supported in the carriage and which are 30 in contact with their corresponding bars, see Figure 2. Wires 25 connect these brushes with the terminals of the motor 11.

Means are provided for simulating the jumping of a live rabbit. This makes the 35 rabbit seem natural to the dogs and increases their excitement during the race. Any suitable means may be provided for this purpose. In the present instance, this is accomplished by supporting the rabbit 12 on an arm 26 which is constructed so that 40 it is capable of swinging upwardly. That is to say, it may be attached by a pivot pin 27 to the lower end of the bracket 17. The bracket has a toe 28 which will support 45 the arm 26 in a horizontal position. The rabbit 12 speeds along close to the ground line 29. Along the ground in the path of the arm 26, we provide abutments 30 at intervals along the path. As the rabbit speeds 50 along, these abutments cause the arm 26 to swing upwardly. This raises the body of the rabbit, after which the body falls again by gravity to its normal level.

In order to facilitate the dismantling of 55 the fence, the rails are preferably secured on the posts by means of counter-sunk bolts 31.

It is understood that the embodiment of 60 the invention described herein is only one of the many embodiments this invention may take, and we do not wish to be limited in the practice of the invention, nor in the claims, to the particular embodiment set forth.

65 What we claim is:

1. In a mechanical dog racing apparatus, the combination of a track in the form of a fence having a top rail, a carriage having wheels running on the top rail and having a bracket extending down on one side of the 70 fence, a motor supported on the said bracket, a wheel driven by the motor and running along the side of the track, said carriage having a bracket extending down on the side of the fence opposite to the first named carriage, and a dog lure supported on the last named bracket. 75

2. In a mechanical dog racing apparatus, the combination of a track in the form of a fence having a top rail, a carriage having 80 wheels running on the top rail and having a bracket extending down on one side of the fence, a motor supported on the said bracket, a wheel driven by the motor and running along the side of the track, said carriage having a bracket extending down on the side of the fence opposite to the first named carriage, a dog lure supported on the last named bracket, and means for guiding the 85 lower end of the last named bracket on the track. 90

3. In a mechanical dog racing apparatus, the combination of a track in the form of a fence having a top rail, a carriage having wheels running on the top rail and having a bracket extending down on one side of the fence, said track having a traction rail on one side, a motor supported on the said bracket, a wheel driven by the motor and running along the traction rail to 100 drive the carriage, said carriage having a bracket extending down on the opposite side of the fence and having a guide roller, said track having a guide rail adjacent the roller for guiding the same, and a dog lure supported on the last named bracket. 105

4. In a mechanical dog racing apparatus, the combination of a track consisting of a fence having a plurality of removable posts with rails removably supported on the posts, a carriage having wheels running on the top rail and having a bracket extending down on one side of the fence, a motor supported on the bracket, a wheel driven by the motor and running along the side of the track to drive the carriage, said carriage having a bracket extending down on the opposite side of the fence, and a dog lure supported on the last named bracket. 110

5. In a mechanical dog racing apparatus, the combination of a track consisting of a fence having posts, means for removably supporting the posts on the ground, removable rails carried on the posts, a carriage supported on the track, a motor supported on the carriage, a wheel running on the track and driven by the motor to drive the carriage, and a dog lure supported on the bracket. 115

6. In a mechanical dog racing apparatus, 120

the combination of a track consisting of a fence having posts, a top rail, and a power rail supported on said posts on one side, said track having a traction rail supported on the 5 same side as the power rail, said track having a guide rail supported on the other side, a carriage having wheels running on the top rail and having a bracket extending down on the side of the track having the power 10 rail, an electric motor supported on the carriage, a wheel supported on the carriage driven by the electric motor and running

on the traction rail to drive the carriage brushes for taking the current to the motor from the power rail, said carriage having 15 a bracket extending down on the side of the track adjacent the guide rail and having a guide roller running on the guide rail, and a dog lure carried by the last named bracket.

Signed at Glendale, Calif., this 18th day 20 of March, 1927.

HAROLD F. WILSON.
ALBERT V. WILSON.
